5-AMINO-3-SUBSTITUTED-1,2,4-THIADIAZOLE
AZO COMPOUNDS

William H. Moore, Edmund B. Towne, and Joseph B. Dickey, Kingsport, Tenn., assignors to Eastman Kodak Company, Rochester, N.Y., a corporation of New Jersey
No Drawing. Filed Nov. 13, 1962, Ser. No. 237,307
7 Claims. (Cl. 260—158)

This invention relates to new monoazo compounds and their application to the art of dyeing or coloring.

While numerous compounds have been proposed as dyes for cellulose alkyl carboxylic acid ester, having 2 to 4 carbon atoms in the acid groups thereof, textile materials, polyester textile materials, nylon textile materials and acrylonitrile polymer textile materials, much time and effort are being expended to find improved dyes for these materials.

It is an object of our invention to provide new monoazo compounds which are dyes for the aforesaid textile materials. Another object is to provide colored textile materials which have good fastness to light, gas and washing, good resistance to sublimation and which undergo little change in color under artificial light. A further object is to provide colored textile materials which discharge to a pure white. Another object is to provide satisfactory means for the preparation of the new monoazo compounds of our invention.

We have discovered that the new monoazo compounds having the formula:

wherein X represents a low carbon alkylthio group or a low carbon alkylsulfonyl group and R represents an aniline coupling component free of a water-solubilizing group are dyes for the aforesaid textile materials. The term "water-solubilizing group" refers to groups such as a sulfonic acid group or a carboxylic acid group, for example. Representative of a low-carbon alkylthio group are methylthio, ethylthio, n-propylthio, isopropylthio, n-butylthio, isobutylthio, sec.-butylthio and tert.-butylthio.

Representative of a low-carbon alkylsulfonyl group are methylsulfonyl, ethylsulfonyl, n-propylsulfonyl, isopropylsulfonyl, n-butylsulfonyl, isobutylsulfonyl, sec.-butylsulfonyl and tert.-butylsulfonyl.

Our new monoazo compounds have good to excellent affinity for cellulose alkyl carboxylic acid ester, having 2 to 4 carbon atoms in the acid groups thereof, textile materials, polyester textile materials, acrylonitrile, polymer textile materials and nylon textile materials and yield dyeings thereon which have good fastness to light, gas and washing, good resistance to sublimation, good dischargeability and which undergo little change in color under artificial light.

The new monoazo compounds of our invention are water-insoluble. They are applied to the aforesaid textile materials by known dyeing techniques. Being water-insoluble they can be applied from aqueous dispersion in the manner of the so-called "disperse dyes." However, coloration can also be effected, for example, by incorporating the azo compounds into the spinning dope and spinning the fiber as usual. The azo compounds of our invention have varying utility as dyes. The degree of utility varies, for example, depending upon the material being dyed and the formula of the azo compound. Thus, for example, all the azo compounds will not have the same degree of utility for the same material.

By cellulose alkyl carboxylic acid esters having 2 to 4 carbon atoms in the acid groups thereof, we mean to

2

include, for example, both hydrolyzed and unhydrolyzed cellulose acetate, cellulose propionate, cellulose butyrate, cellulose acetate-propionate and cellulose acetate-butyrate.

5 Insofar as polyester textile materials are concerned, our invention is primarily directed to the dyeing of linear aromatic polyester textile materials having a melting point of at least 200° C.

Linear aromatic polyester textile materials that can be dyed with the new azo compounds of our invention include polyethylene terephthalate textile materials obtained, for example, as described in U.S. Patent 2,465,319 patented March 22, 1949, or polyester textile materials formed from other fiber-forming linear polyesters, such as polyesters derived from p,p'-diphenylsulfonedicarboxylic acid and various aliphatic acids and glycols as described in U.S. Patent 2,744,088 patented May 1, 1956, and polyesters derived from various acids, such as terephthalic acid and 1,4-cyclohexanedimethanol (1,4-dimethylolcyclohexane) as described in Kibler, Bell and Smith U.S. Patent 2,901,466.

The polyester materials sold under the trademarks "Kodel," "Dacron" and "Terylene," for example, in the form of filaments, yarn and fabric, for example, are illustrative of the linear polyester textile materials that can be dyed. Kodel polyester materials are more particularly described in U.S. Patent 2,901,466. Dacron and Terylene polyester materials are described, for example, in U.S. Patent 2,465,319. The polyester textile materials specifically referred to hereinbefore are linear aromatic polyesters having a melting point of at least 200° C. Linear aromatic polyesters having a lower melting point than 200° C. can also be dyed or colored with the new azo compounds of our invention. U.S. Patents 2,945,010, 2,957,745 and 2,989,363 also disclose polymeric linear polyester materials that can be dyed.

Unless otherwise indicated, the term "acrylonitrile polymer" as used herein includes polymers consisting essentially of polymerized acrylonitrile (i.e., acrylonitrile polymers containing at least 85% by weight of acrylonitrile) as well as modified acrylonitrile polymers known in the art as modacrylics. The modacrylics contain at least 40% but less than 85% acrylonitrile by weight. U.S. Patents 2,811,409, 2,831,826 and 2,843,572 disclose modacrylic fibers that can be dyed with our new monoazo compounds. Our new monoazo compounds are particularly suited for the dyeing of modacrylic textile materials.

The acrylonitrile polymer materials sold under the trademarks "Verel," "Orlon" and "Acrilan," in the form of filaments, yarn and fabric, for example, are illustrative of the acrylonitrile polymer textile materials that can be dyed with our new monoazo compounds.

The new monoazo compounds of our invention are prepared by diazotizing a 5-amino-3-substituted-1,2,4-thiadiazole compound having the formula:

60 wherein X represents a low carbon alkylthio or a low carbon alkylsulfonyl group and coupling the diazonium compound obtained with an aniline coupling component free of a water-solubilizing group.

While our invention relates broadly to the new monoazo compounds having Formula I, it relates more particularly to the monoazo compounds having the formula:

wherein X has the meaning previously assigned to it, R₁ and R₂ each represents a hydrogen atom, an alkyl radical having 1 to 4 carbon atoms, a hydroxyalkyl group having 2 to 4 carbon atoms, an alkoxyalkyl group having 3 to 4 carbon atoms, a cyanoalkyl group having 3 to 5 carbon atoms, an acetoxyalkyl group having 4 to 6 carbon atoms, a carbomethoxymethyl group, a carboethoxy-methyl group, a β -carbomethoxyethyl group, a β -carboethoxyethyl group, a 2-bromoethyl group, a 2-chloroethyl, a 2,2-difluoroethyl group, a 2,2-difluoro-n-propyl group, a 3,3-difluoropropyl group, a 3,3-difluoro-n-butyl, a 2,2,2-trifluoroethyl, a 3,3,3-trifluoropropyl group, a 4,4,4-trifluorobutyl group, an alkenyl group having 3 to 4 carbon atoms, a chloroalkenyl group having 3 to 4 carbon atoms, a bromoalkenyl group having 3 to 4 carbon atoms, a 2,3-epoxypropyl group, an N- β -(phenylcarbamyl-oxo)ethyl group, an N- β -(phenylthiocarbamyl-oxo)ethyl group, a low carbon alkylcarbamyl-oxoethyl group or a low carbon alkylthiocarbamyl-oxoethyl group, Q represents a hydrogen atom, a bromine atom, a chlorine atom, a methyl group, an ethyl group, a methoxy group, an ethoxy group, an acetamido group, an n-propionylamino group or an n-butyrylamino group, and Y represents a hydrogen atom, a methyl group, an ethyl group, a methoxy group, an ethoxy group, a chlorine atom or a bromine atom.

Illustrative of the 5-amino-1,2,4-thiadiazole compounds used in preparing the new monoazo compounds of our invention are

5-amino-3-methylthio-1,2,4-thiadiazole,
5-amino-3-ethylthio-1,2,4-thiadiazole,
5-amino-3-n-propylthio-1,2,4-thiadiazole,
5-amino-3-isopropylthio-1,2,4-thiadiazole,
5-amino-3-n-butylthio-1,2,4-thiadiazole,
5-amino-3-isobutylthio-1,2,4-thiadiazole,
5-amino-3-sec.-butylthio-1,2,4-thiadiazole,
5-amino-3-tert.-butylthio-1,2,4-thiadiazole,
5-amino-3-methylsulfonyl-1,2,4-thiadiazole,
5-amino-3-ethylsulfonyl-1,2,4-thiadiazole,
5-amino-3-n-propylsulfonyl-1,2,4-thiadiazole,
5-amino-3-isopropylsulfonyl-1,2,4-thiadiazole,
5-amino-3-n-butylsulfonyl-1,2,4-thiadiazole,
5-amino-3-isobutylsulfonyl-1,2,4-thiadiazole,
5-amino-3-sec.-butylsulfonyl-1,2,4-thiadiazole and
5-amino-3-tert.-butylsulfonyl-1,2,4-thiadiazole.

Illustrative of the alkyl groups represented by R₁ and R₂ are methyl, ethyl, n-propyl, isopropyl and n-butyl. Similarly, β -hydroxyethyl, β -hydroxypropyl, γ -hydroxypropyl, β , γ -dihydroxypropyl, β -methyl- β , γ -dihydroxypropyl and δ -hydroxybutyl are illustrative of the hydroxyalkyl groups R₁ and R₂ represent.

Illustrative of the alkoxyalkyl groups represented by R₁ and R₂ are β -methoxyethyl and β -ethoxyethyl. Similarly, β -cyanoethyl, γ -cyanopropyl and δ -cyanobutyl groups are illustrative of the cyanoalkyl groups R₁ and R₂ represent.

Allyl, propenyl, isopropenyl, 1-but enyl, 2-but enyl and 3-but enyl are illustrative of the alkenyl groups represented by R₂. Chloroallyl ($-\text{CH}_2\text{CH}=\text{CHCl}$), bromoallyl ($-\text{CH}_2\text{CH}=\text{CHBr}$), 4-chloro-3-but enyl ($-\text{CH}_2\text{CH}_2\text{CH}=\text{CHCl}$) and 3-bromo-3-but enyl are illustrative of halogenated alkenyl groups. Illustrative of the low carbon alkyl carbamyl-oxoethyl and arylcarbamyl-oxoethyl groups are β -methylcarbamyl-oxoethyl, β -ethylcarbamyl-oxoethyl, β -n-propylcarbamyl-oxoethyl, β -n-butylcarbamyl-oxoethyl and β -phenylcarbamyl-oxoethyl, for example. Illustrative of the low carbon alkyl thiocarbamyl-oxoethyl and arylthiocarbamyl-oxoethyl groups are β -methylthiocarbamyl-oxoethyl, β -ethylthiocarbamyl-oxoethyl, β -n-propylthiocarbamyl-oxoethyl, β -n-butylthiocarbamyl-oxoethyl and β -phenylthiocarbamyl-oxoethyl, for example.

Typical of the aniline coupling components used in

the preparation of the azo compounds of our invention are

aniline,
m-toluidine,
m-anisidine,
m-chloroaniline,
2-methoxy-5-chloroaniline,
2,5-dimethoxyaniline,
2-methoxy-5-methylaniline,
10 N- β -hydroxyethylaniline,
N- β -hydroxypropylaniline,
N- β , γ -dihydroxypropylaniline,
N- γ -hydroxypropylaniline,
N- δ -hydroxybutylaniline,
15 N- β -hydroxyethyl-o-chloroaniline,
N- β -hydroxyethyl-o-methoxyaniline,
N- β -cyanoethylaniline,
N- β -methoxyethylaniline,
N- β -ethoxyethylaniline,
20 N- β -carboethoxyethyl-m-toluidine,
N- β -carboethoxyethyl-m-chloroaniline,
N,N-di- β -hydroxyethylaniline,
N,N-di- β -hydroxyethyl-m-chloroaniline,
N,N-di- β -hydroxyethyl-m-toluidine,
N-ethyl-N- β , γ -dihydroxypropyl-m-toluidine,
N-ethyl-N-(β -methyl- β , γ -dihydroxypropyl)aniline,
N-methyl-N- β , γ -dihydroxypropyl-m-toluidine,
N- β -methoxyethyl-N- β , γ -dihydroxypropyl-m-toluidine,
25 N,N-di- β -hydroxyethyl-m-bromoaniline,
N-ethyl-N- δ -hydroxybutylaniline,
N- β -hydroxyethyl-N- β , β -trifluoroethylaniline,
N- β -hydroxyethyl-N- γ , γ -trifluoropropylaniline,
N- β -hydroxyethyl-N- δ , δ -trifluorobutylaniline,
30 N- β -hydroxyethyl-N- β , β -difluoroethylaniline,
N- β -hydroxypropyl-N- γ , γ -difluoropropylaniline,
N- β -hydroxyethyl-N- β , β -difluoropropylaniline,
N- β , γ -dihydroxypropyl-N- γ , γ -difluorobutylaniline,
N- β , γ -dihydroxypropyl-N- δ , δ -difluoroamylaniline,
35 N-methyl-N- β -hydroxyethyl-m-bromoaniline,
N,N-di- β -hydroxyethyl-2,5-dieethoxyaniline,
N,N-di- β -hydroxyethyl-2,5-dichloroaniline,
N-n-propyl-N- β -hydroxyethylaniline,
N-isopropyl-N- β -hydroxyethylaniline,
N-n-butyl-N- β -hydroxyethylaniline,
40 N- β -hydroxyethyl-N-cyanoethyl-m-chloroaniline,
N- β -hydroxyethyl-N- γ -cyanopropylaniline,
N- β -carboethoxyethylaniline,
N- β -carboethoxyethyl-N- β -hydroxyethylaniline,
N- β -carboethoxyethyl-N- β -hydroxyethyl-m-chloroaniline,
45 N- β -hydroxyethyl-N- β -chloroallylaniline,
N- β -hydroxyethyl-N- β -nitroethylaniline,
N-methyl-N- β -chloroethylaniline,
N-ethyl-N- β -chloroethylaniline,
50 N-ethyl-N- β -chloroethyl-m-chloroaniline,
N- β -hydroxyethyl-N- β -chloroethylaniline,
N-ethyl-N- β -bromoethylaniline,
N-ethyl-N- β -bromoethyl-m-anisidine,
N-ethyl-N- β -(phenylthiocarbamyl-oxo)ethyl-m-chloroaniline,
55 N- β -hydroxyethyl-N- β -(methylcarbamyl-oxo)ethyl-aniline,
N-ethyl-N- β -(ethylcarbamyl-oxo)ethyl-m-toluidine,
N-ethyl-N- β -(ethylthiocarbamyl-oxo)ethyl-aniline,
60 N-ethyl-N- β -(methylthiocarbamyl-oxo)ethyl-2,5-dimethoxyaniline,
N-methyl-N-(2,3-epoxypropyl)aniline,
N-ethyl-N-(2,3-epoxypropyl)aniline,
N,N-di-(2,3-epoxypropyl)aniline,
65 N,N-di-(β -chloroethyl)aniline,
N-n-(β -bromoethyl)aniline,
N-ethyl-N-(γ -chloro- β -hydroxypropyl)aniline,
N,N-di-(γ -bromo- β -hydroxypropyl)aniline and
N- β -methoxyethyl-N-(γ -chloro- β -hydroxypropyl)aniline.

The 5-amino-3-alkylthio-1,2,4-thiadiazole compounds used in the preparation of the monoazo compounds of our invention can be prepared by reacting a 2-alkyl-2-thiopseudourea salt with NaSCN in the presence of bromine and sodium methoxide in methanol as described in Ber., 89, 2742 (1956). The 3-alkylsulfonyl derivatives can be obtained by oxidizing the 3-alkylthio compounds as described in Ber., 89, 2747 (1956). We prefer however to use H_2O_2 as the oxidizing agent instead of the phthalic monoperacid of the reference.

The following examples illustrate our invention.

Example 1.—Preparation of 5-amino-3-methylthio-1,2,4-thiadiazole

A. In a 3-l.,3-necked flask, equipped with a mechanical stirrer, thiourea (76 grams), methyl iodide (142 grams), and anhydrous methanol (330 ml.) were stirred together. As soon as complete solution occurred, the reaction mixture began to warm up, after which it was heated on a steam bath. After stirring at reflux for one hour, the condenser was set for distillation, and approximately 70 ml. of the volatile materials were distilled to remove any excess methyl iodide. The solution containing 2-methyl-2-thiopseudourea was cooled to room temperature and a solution of sodium thiocyanate (100 grams) in anhydrous methanol (600 ml.) was added. The resulting solution was cooled to $-15^{\circ} C.$ by means of a Dry Ice-acetone bath. The flask was equipped with two dropping funnels. In one was placed a cold sodium methoxide solution prepared by dissolving sodium (46 grams) in anhydrous methanol (600 ml.); in the other funnel was placed a cold solution of bromine (160 grams) in anhydrous methanol (425 ml.). With vigorous stirring, approximately $\frac{1}{2}$ of the methoxide solution was run into the flask, then both solutions were added at the same rate during $1\frac{1}{2}$ hours, keeping the temperature below $-5^{\circ} C.$ When the addition was completed, the cooling bath was removed and the reaction mixture stirred for two hours at room temperature. The faintly alkaline solution was neutralized with concentrated HCl and the reaction mixture evaporated to dryness under reduced pressure. The residue was extracted with water to remove inorganic salts, then recrystallized from water with addition of charcoal. The weight of product was 104 grams (71%), melting at $139-42^{\circ} C.$

Calculated for 5-amino-3-methylthio-1,2,4-thiadiazole: C=24.49%, H=3.40%, S=43.54%. Found: C=24.70%, H=3.49%, S=43.34%.

B. 2-methyl-2-thiopseudourea sulfate, prepared as in Org. Syn. Coll., vol. II, p. 411, was substituted for the above in situ preparation of 2-methyl-2-thiopseudourea hydrogen iodide to give a 71% yield of the 5-amino-3-methylthio-1,2,4-thiadiazole.

Example 2.—Preparation of 5-amino-3-ethylthio-1,2,4-thiadiazole

30 grams of sodium thiocyanate were dissolved in 250 ml. of methanol with good stirring. To this were added with stirring 54.5 grams of 2-ethyl-2-thiopseudourea hydrobromide (Org. Syn. Coll., vol. III, p. 440). After chilling to $-14^{\circ} C.$, this solution of sodium thiocyanate and 2-ethyl-2-thiopseudourea hydrobromide was treated simultaneously from two separate dropping funnels containing solutions of (1) bromine (48 grams) in 140 ml. of methanol and (2) sodium methylate in methanol, prepared from sodium (13.8 grams) in 150 ml. of methanol. The reaction mixture was stirred and cooled, and the additions were at such a rate as to keep the temperature at $-5^{\circ} C.$ and took 1 hour. About $\frac{1}{2}$ of the sodium methylate solution was added first, after which the two solutions were added simultaneously. The reaction was stirred 1 hour more without cooling after the addition was complete. The reaction mixture was slightly alkaline and was carefully neutralized with concentrated HCl. It was then filtered from a small amount of precipitated NaBr.

The methanol was removed in vacuo, and the resulting solid residue was triturated and washed twice with water and then air dried. The crude product weighed 39.5 grams (81.7%) and melted at $74-92^{\circ} C.$ Crystallization from 100 ml. of water yielded 30 grams of product, M.P. $90-5^{\circ} C.$, softening point $60^{\circ} C.$ Recrystallization from benzene-hexane yielded 26.2 grams of 5-amino-3-ethylthio-1,2,4-thiadiazole in the form of white needles melting at $92-6^{\circ} C.$

Example 3.—Preparation of 5-amino-3-n-propylthio-1,2,4-thiadiazole

A solution of 76 grams of thiourea and 123 grams of n-propylbromide in 330 ml. of methanol was heated with stirring on a steam bath under reflux for 2 hours. The reaction mixture was then distilled until 50 cc. of solvent had been removed, thus assuring complete removal of any excess n-propylbromide (B.P. $70^{\circ} C.$). If it is desired to isolate 2-n-propyl-2-thiopseudourea hydrobromide at this stage, the solution is further concentrated and then cooled. A white crystalline product is obtained which melts at $59-61^{\circ} C.$ when crystallized from alcohol-ether. (See Bellock and Witt, J. Agric. & Food Chem., 1176 (1954); CA 49, 3463 (1955)).

In order to prepare 5-amino-3-n-propylthio-1,2,4-thiadiazole, the above methanol solution of 2-n-propyl-2-thiopseudourea hydrobromide was treated in a 3-liter flask with a solution of 100 grams of sodium thiocyanate in 600 ml. of anhydrous methanol at room temperature. The solution was then cooled to $-15^{\circ} C.$ and stirred vigorously as the addition of the sodium methoxide solution (46 grams metallic sodium in 600 ml. anhydrous methanol) and of the cold solution of bromine (160 grams bromine in 425 ml. of cold anhydrous methanol) was carried out exactly as described in Example 1 at $-5^{\circ} C.$ After the addition was complete, the reaction mixture was stirred two hours at room temperature after which it was neutralized with concentrated hydrochloric acid and then evaporated to dryness under reduced pressure.

The residue was extracted with cold water to remove inorganic salts and then was crystallized from water, using charcoal. The dried, tan product weighed 135 grams (77.2%) and melted at $74^{\circ} C.$ when crystallized from aqueous ethanol.

Example 4.—Preparation of 5-amino-3-isopropylthio-1,2,4-thiadiazole

A methanolic solution of 28.2 grams of thiourea and 46 grams of isopropyl bromide were heated on the steam bath as described in Example 3 and yielded a practically quantitative yield of 2-isopropylthiopseudourea, M.P. $76-8^{\circ} C.$ Treatment of a solution of this product with sodium thiocyanate, bromine and sodium methoxide in accordance with the procedure described in Example 1 gave a good yield of 5-amino-2-isopropylthio-1,2,4-thiadiazole.

Example 5.—Preparation of 5-amino-3-tert.-butylthio-1,2,4-thiadiazole

Example 4 was repeated using 70 grams of tert.-butyl bromide in place of isopropyl bromide. Crystalline 5-amino-3-tert.-butylthio-1,2,4-thiadiazole melting at $203^{\circ} C.$ was obtained. (See Ber., 89, 2742 (1946).)

In a similar manner there were prepared:

5-amino-3-n-butylthio-1,2,4-thiadiazole
5-amino-3-isobutylthio-1,2,4-thiadiazole
5-amino-3-sec.-butylthio-1,2,4-thiadiazole

Example 6.—Preparation of 5-amino-3-methylsulfonyl-1,2,4-thiadiazole

5-amino-3-methylthio-1,2,4-thiadiazole (7.35 grams) was dissolved in acetic acid (100 ml.) by warming gently on the steam bath. The solution was cooled to $30^{\circ} C.$, and 30% hydrogen peroxide (20.5 grams, a 20% excess) was added all at once, causing precipitation of a white solid. The mixture was stirred and warmed gently to

effect solution. Solution occurred at about 50° C., and the temperature then rose spontaneously to 70° C. The solution was stirred until the temperature dropped to 25° C., and was then concentrated to about 1/4 its volume under reduced pressure. On standing, 5-amino-3-methylsulfonyl-1,2,4-thiadiazole precipitated as a white solid and was recovered by filtration, washed with water and air dried. It weighed 5.4 grams (65.2%) and had a melting point of 196.8° C.

Calculated for 5-amino-3-methylsulfonyl-1,2,4-thiadiazole: C=20.11%, H=2.80%, S=35.75%. Found: C=20.18%, H=3.00%, S=35.67%.

Example 7.—Preparation of 5-amino-3-ethylsulfonyl-1,2,4-thiadiazole

8.05 grams of 5-amino-3-ethylthio-1,2,4-thiadiazole prepared in Example 2 and melting at 92–6° C. were oxidized to the sulfonyl compound using monoperphthalic acid as described in Ber., 89, 2747 (1956). 1.2 grams of crystallized 5-amino-3-ethylsulfonyl-1,2,4-thiadiazole were obtained, melting at 136–9° C.

Example 8.—Preparation of 5-amino-3-n-propylsulfonyl-1,2,4-thiadiazole

8.7 grams of 5-amino-3-n-propylthio-1,2,4-thiadiazole prepared in Example 3 were dissolved in 100 ml. of acetic acid. To this solution at room temperature were added all at once 20.5 grams of 30% hydrogen peroxide, which is a 20% excess over theoretical. The mixture was then stirred and warmed gently on a steam bath to effect solution of the precipitate. Solution was effected at 50° C., and the temperature then rose spontaneously to 70° C. Stirring was then continued for one hour while allowing the temperature to fall to 25° C. The reaction mixture was then concentrated to about 1/4 its volume under reduced pressure. On standing, a white solid separated which, after filtering, washing and drying, yielded 6.5 grams of 5-amino-3-n-propylsulfonyl-1,2,4-thiadiazole.

Example 9.—Preparation of 5-amino-3-tert.-butylsulfonyl-1,2,4-thiadiazole

Example 8 was repeated using 9.4 grams of 5-amino-3-tert.-butyl-1,2,4-thiadiazole in place of 5-amino-3-n-propylsulfonyl-1,2,4-thiadiazole. 6.9 grams of 5-amino-3-tert.-butylsulfonyl-1,2,4-thiadiazole were obtained.

In a similar manner there were prepared:

5-amino-3-n-butylsulfonyl-1,2,4-thiadiazole
5-amino-3-isobutylsulfonyl-1,2,4-thiadiazole
5-amino-3-sec.-butylsulfonyl-1,2,4-thiadiazole.

Example 10

A. Diazotization.—Nitrosyl sulfuric acid was prepared by adding 1.52 grams (0.022 mole) of sodium nitrite portionwise and with vigorous stirring to 10 ml. of concentrated sulfuric acid. The temperature of the reaction mixture was not allowed to rise above 65° C. The resulting solution was then cooled to 5° C., and 20 ml. of a mixture of 3 ml. of n-propionic acid and 17 ml. of acetic acid were added dropwise, with stirring, while allowing the temperature to rise to 15° C. and maintaining the solution at this temperature during the remainder of the addition.

The nitrosylsulfuric acid mixture was cooled to 0°–5° C., and 2.94 grams (0.02 mole) of 5-amino-3-methylthio-1,2,4-thiadiazole were added thereto portionwise, with stirring, after which 20 ml. more of the propionic-acetic acid mixture was added, keeping the temperature at 0–5° C. The reaction mixture was then stirred at 0–5° C. for 2 hours, and the excess sodium nitrite was destroyed by adding 1 gram of urea. A clear diazonium solution was thus obtained.

B. Coupling.—10 ml. of the 5-amino-3-methylthio-1,2,4-thiadiazole diazonium solution prepared as described in 10A were added, with stirring, at 0°–5° C. to a solution of 0.82 gram of N-β-cyanoethyl-N-β-hydroxy-

ethyl-m-toluidine in 10 ml. of the propionic-acetic acid mixture, cooled to 0° C. When the addition was completed, the reaction mixture was made neutral to Congo red paper by the addition of solid, anhydrous sodium acetate. The neutralized coupling mixture was allowed to stand in an ice bath for one hour, with occasional stirring, and then was diluted with 250 parts of cold water, with good stirring. The dye compound which precipitated was recovered by filtration, washed with water until neutral and air dried. It has the formula:

The dye obtained weighed 1.02 grams (70.3%). It dyed cellulose acetate fabric bright red shades having excellent fastness to light, linear aromatic polyester fabric orange-red shades having good fastness to light, and acrylonitrile polymer fabric and nylon fabric red-violet shades having good light fastness.

Example 11

A solution of 0.57 gram N-ethyl-N-β-(phenylcarbamoyloxy)-ethylaniline in 5 ml. of a 6:1 propionic-acetic acid mixture was coupled according to the procedure of Example 10B with 5 ml. of a 5-amino-3-methylthio-1,2,4-thiadiazole diazonium solution prepared as in Example 10A. The dye obtained weighed 0.69 gram (78.5%) and dyed cellulose acetate fabric reddish-pink, linear aromatic polyester fabric orange-red, Verel modacrylic fabric wine-red, and nylon fabric red. Light fastness was excellent on all these fabrics.

Example 12

5 ml. of the diazonium solution prepared as in Example 10A were coupled with 0.51 gram of N-ethyl-N-(β-methanesulfonamido)-ethyl-m-toluidine in accordance with the procedure of Example 10B. There was obtained 0.56 gram (67.5%) of dye which colored cellulose acetate fabric red-violet, linear aromatic polyester fabric red-pink, Verel modacrylic fabric violet, and nylon fabric violet, all with excellent light fastness.

Example 13

5 ml. of the diazonium solution prepared as in Example 10A were coupled with 0.44 gram of N-cyclohexyl-N-β-hydroxyethylaniline in accordance with the procedure of Example 10B to give 0.48 gram (64%) of product. The dye compound obtained colored cellulose acetate fabric red-violet, linear aromatic polyester fabric red, Verel modacrylic fabric violet and nylon fabric violet-red. The fastness to light was excellent on the cellulose acetate, very good on the linear aromatic polyester, good on nylon and fair on the Verel modacrylic fabric.

Example 14

1.79 grams (0.01 mole) of 5-amino-3-methylsulfonyl-1,2,4-thiadiazole were diazotized in accordance with the general procedure described in Example 10A using the molar proportions of reactants indicated in Example 10A. 25 ml. of diazonium solution were obtained.

5 ml. of the diazonium solution thus obtained were coupled with 0.38 gram of N-ethyl-N-β-cyanoethyl-m-toluidine. Coupling and recovery of the azo dye compound formed were carried out in accordance with the general procedure described in Example 10B. The yield of dye was 0.28 gram (37.2%). It dyed cellulose acetate fabrics a bright red-violet shade with excellent light fastness, linear aromatic polyester fabric a bright pinkish-red with very good light fastness, and Verel modacrylic fabric a deep red-violet with excellent light fastness.

Example 15

0.43 gram of N-β-cyanoethyl-N-benzylaniline was coupled with 5 ml. of a 5-amino-3-methylsulfonyl-1,2,4-thia-

diazole diazonium solution prepared as in Example 14. Coupling and recovery of the azo dye compound formed were carried out in accordance with the general procedure described in Example 10B. The yield of dye was 0.56 gram (67%). It dyed cellulose acetate fabrics deep wine-red shades having excellent fastness to light. The dyeing obtained on modacrylic fabric had good to excellent fastness to light.

Example 16

10 ml. of a 5-amino-3-methylsulfonyl-1,2,4-thiadiazole diazonium solution obtained as described in Example 14 were coupled with 0.92 gram (0.004 mole) of N- β -cyanoethyl-N- β -hydroxyethyl-m-toluidine. Coupling and recovery of the azo compound formed were carried out in accordance with the general procedure described in Example 10B. The azo dye compound obtained colored cellulose acetate fabrics deep wine-red shades having excellent fastness to light. The dyeing obtained on modacrylic fabrics also had excellent fastness to light.

Example 17

0.02 gram mole of 5-amino-3-ethylthio-1,2,4-thiadiazole was diazotized in accordance with the procedure described in Example 10A and the diazonium compound obtained was coupled with 0.01 gram mole of N,N-(di- β -hydroxyethyl)-2-methoxy-5-acetamidoaniline. Coupling and recovery of the azo compound formed were carried out in accordance with the procedure described in Example 10B. The violet azo dye compound obtained has excellent affinity for linear aromatic polyester and cellulose acetate fabrics. The dyeings obtained on cellulose acetate fabric have good fastness to light.

Example 18

0.01 gram mole of 5-amino-3-ethylthio-1,2,4-thiadiazole was diazotized in accordance with the general procedure described in Example 10A and the diazonium compound obtained was coupled with 0.01 gram mole of N- β -hydroxyethyl-N- β , β -difluoroethyl-m-toluidine. Coupling and recovery of the red azo dye compound formed were carried out in accordance with the general procedure described in Example 10B. The dye compound thus obtained has good affinity for cellulose acetate and linear aromatic polyester fabrics and yielded dyeings thereon having good fastness to light.

Example 19

0.01 gram mole of 5-amino-3-ethylsulfonyl-1,2,4-thiadiazole was diazotized in accordance with the general procedure described in Example 10A and the diazonium compound obtained was coupled with 0.01 gram mole of N,N-di- β -hydroxyethyl-m-chloroaniline. Coupling and recovery of the azo dye compound formed were carried out in accordance with the general procedure described in Example 10B. The dye compound thus obtained dyes cellulose acetate, linear aromatic polyester, nylon and modacrylic fabrics red-violet shades having good fastness to light.

Example 20

0.5 gram of the dye prepared in Example 10 by coupling diazotized 5-amino-3-methylthio-1,2,4-thiadiazole with N- β -cyanoethyl-N- β -hydroxyethyl-m-toluidine was dissolved in 20 ml. of acetic acid and treated with 1.0 gram of acetic anhydride and heated on the steam bath for 1 hour. Upon drowning in water, an acetylated dye precipitated and was recovered by filtration, washed with water and dried. It dyed the various fabrics essentially the same shades as did the unacetylated dye of Example 10, but the dyeings were somewhat faster to light, especially on polyester fabrics, and also had a higher degree of wash and sublimation fastness. This dye is the acetoxy derivative of the dye of Example 10 in which the N- β -hydroxyethyl group of the coupler has been acetylated.

Example 21

The dye of Example 20 was also obtained by coupling diazotized 5-amino-3-methylthio-1,2,4-thiadiazole with the pre-acetylated coupler, N- β -cyanoethyl-N- β -acetoxyethyl-m-toluidine. This dye had the same excellent affinity, and gave dyeings on cellulose acetate, linear aromatic polyester, nylon and modacrylic fabrics having the same shades and good fastness to light as those obtained with the dye of Example 20.

Example 22

0.5 gram of the dye prepared in Example 19 was acetylated with acetic anhydride in accordance with the procedure described in Example 20. The resulting acetylated dye gave red-violet shades on linear aromatic polyester, cellulose acetate, nylon and modacrylic fabrics which have good fastness to light.

Example 23

20 0.5 gram of the dye compound prepared in Example 10 was heated in 20 ml. of dry benzene solution with 1.0 gram of phenylisothiocyanate for 1 hour on a steam bath. The resulting new dye contained a phenylthiocarbamate group in the coupler and had excellent affinity and good light fastness on cellulose acetate, linear aromatic polyester, nylon and modacrylic fabrics. The dye compound obtained has the formula:

The dye compound of this example can also be prepared by coupling diazotized 5-amino-3-methylthio-1,2,4-thiadiazole with the preformed coupling component.

Example 24

35 3.5 grams of 5-amino-3-n-propylthio-1,2,4-thiadiazole were diazotized using the procedure of Example 10A. 10 ml. of the diazonium solution obtained were coupled with 1.05 grams of N-(β , γ -dihydroxypropyl)-2-ethoxy-5-acetamidoaniline. Coupling and recovery of the azo dye compound formed were carried out in accordance with the general procedure described in Example 10B. 1.23 grams of an azo dye compound which dyed cellulose acetate, linear aromatic polyester, nylon and modacrylic fabrics deep violet shades having good fastness to light and gas, for example, were obtained.

Example 25

40 50 3.78 grams of 5-amino-3-tert-butyldisulfonyl-1,2,4-thiadiazole were diazotized using the procedure of Example 10A. 10 ml. of the diazonium solution obtained were coupled with 0.82 gram of N- β -cyanoethyl-N- β -hydroxyethyl-m-toluidine. Coupling and recovery of the azo dye compound formed were carried out in accordance with the general procedure described in Example 10B. The dye compound thus obtained dyed cellulose acetate fabrics deep wine-red shades having excellent fastness to light. The dyeing obtained on Verel modacrylic fabric also had excellent fastness to light.

Examples 26-35

In the same manner as in Examples 24 and 25 the 5-amino-1,2,4-thiadiazole compounds containing the

- 65 (26) isopropylthio,
 (27) isopropylsulfonyl,
 (28) sec.-butylthio,
 (29) sec.-butylsulfonyl,
 (30) isobutylthio,
 (31) isobutylsulfonyl,
 (32) tert.-butylthio,
 (33) n-propylsulfonyl,
 (34) n-butylthio and the
 70 (35) n-butylsulfonyl

groups, respectively, in the 3-position were diazotized and the diazonium compounds obtained were coupled, respectively, with the following aniline coupling compounds.

- (26) N-ethyl-N- β -(phenylcarbamyl)oxyethyl-aniline
- (27) N-ethyl-N- β -(methanesulfonamido)ethyl-m-toluidine,
- (28) N-cyclohexyl-N- β -hydroxyethylaniline,
- (29) N-ethyl-N- β -cyanoethyl-m-toluidine,
- (30) N- β -cyanoethyl-N-benzylaniline,
- (31) N- β -cyanoethyl-N- β -hydroxyethyl-m-toluidine,
- (32) N- β -cyanoethyl-N- β -acetoxymethyl-m-toluidine,
- (33) N,N-(di- β -hydroxyethyl)-2-methoxy-5-acetamidoaniline,
- (34) N- β -hydroxyethyl-N- β , β -difluoroethyl-m-toluidine and
- (35) N,N-di- β -hydroxyethyl-m-chloroaniline.

Diazotization, coupling and recovery of the monoazo dye compounds formed were carried out in accordance with the procedure set forth in Example 10. The dye compounds obtained dyed cellulose acetate, acrylonitrile polymer, linear aromatic polyester and nylon textile materials dark red to violet shades which had good fastness to light.

Following the procedure described hereinbefore, the monoazo dye compounds indicated hereinafter were prepared. The color stated is that which is obtained on linear aromatic polyester textile materials. Nylon, cellulose alkyl carboxylic acid ester, having 2 to 4 carbon atoms in the acid groups thereof, and acrylonitrile polymer textile materials are dyed shades that are shifted somewhat more toward blue.

of our invention on four different types of fabrics or textile materials. This dye has the formula:

	Fabric	Color	Affinity	Light
Cellulose Acetate	Pink	Good	Excellent.	
Linear Aromatic Polyester	Orange-red	do	Good.	
Modacrylic	Deep wine-red	do	Excellent.	
Nylon	Deep red	do	Do.	

In the preceding table, the column headed "Light" refers to the light fastness of the dyeing.

Another representative dye having equally good affinity and light fastness as the dye just noted is that prepared by coupling diazotized 5-amino-3-methylthio-1,2,4-thiadiazole with N-ethyl-N- β -(methanesulfonamido)ethyl-m-toluidine. This dye has the formula:

Diazonium compound	Coupling component	Color
5-Amino-3-methylthio-1,2,4-thiadiazole	N-ethyl-N-2,3-dihydroxy-propyl-m-toluidine	Violet-red.
Do	N,N-di- β -hydroxyethyl-m-chloroaniline	Orange-red.
Do	N,N-di- β -hydroxyethyl-3-methoxy-5-acetamidoaniline	Red-violet.
Do	N- β -difluoroethyl-N- β -hydroxyethylaniline	Orange-red.
Do	N- β -cyanoethyl-N- β -hydroxyethylaniline	Orange.
Do	N-ethyl-N- β -hydroxyethylaniline	Red.
Do	N-ethyl-N- β -hydroxyethyl-m-toluidine	Do.
Do	N,N-di- β -hydroxyethylaniline	Red-pink.
Do	N- β -hydroxyethyl- α -chloroaniline	Orange.
Do	N- β -hydroxyethyl-m-chloroaniline	Do.
Do	N- β -cyanoethyl-2,5-dichloroaniline	Do.
Do	N-bezyl-N- β -cyanoethylaniline	Do.
Do	N- β -hydroxyethyl-N-(β -methoxycarbonyl-ethyl)-m-chloroaniline	Pink.
Do	N-2,3-dihydroxypropyl-N-(β -methoxycarbonyl-ethyl)-m-chloroaniline	Do.
Do	N- β -cyanoethyl-m-toluidine	Orange-red.
Do	N- β -cyanoethyl-N- β -acetoxymethylaniline	Orange.
Do	N- β -hydroxyethyl-N- β -(methanesulfonamido)ethyl-aniline	Pink.
Do	N- β -cyanoethyl-N- β -hydroxyethyl- α -anisidine	Red-pink.
Do	N- β -cyanoethylaniline	Red.
Do	N-ethyl-N- β -cyanoethyl-m-toluidine	Red.
Do	N,N-di- β -cyanoethyl-m-toluidine	Orange.
Do	N,N-di-(n-butyl)-m-toluidine	Red-pink.
Do	N- β -cyanoethyl-N- β -(methanesulfonamido)ethyl-aniline	Orange.
Do	N- β -cyanoethyl-N-cyclohexyl-aniline	Red-orange.
Do	N- β -cyanoethyl-3-methoxydiphenylamine	Red.
Do	N-ethyl-N-cyclohexylaniline	Do.
Do	N-benzyl-N-cyclohexylaniline	Red-Pink.
Do	N- β -hydroxyethyl-N-cyanomethylaniline	Orange.
Do	N- β -(methanesulfonamido)ethyl-aniline	Do.
Do	N- β -hydroxyethyl-N- β -(methanesulfonamido)ethyl-aniline	Pink.
Do	N,N-di- β -hydroxyethyl-2-methoxy-5-chloroaniline	Red-violet.
Do	N-methyl-N- β -(phenylcarbamyl)oxyethyl-m-toluidine	Scarlet.
Do	N- β -cyanoethyl-N- β -(phenylcarbamyl)oxyethyl-m-toluidine	Orange.
Do	N- β -hydroxyethyl-N- β -cyanoethyl-m-toluidine	Pink.
Do	N- β -hydroxyethyl-N- β -cyanoethyl-N- β -cyanoethylaniline	Do.
Do	N-benzyl-N- β -cyanoethylaniline	Do.
Do	N-ethyl-N- β -(methanesulfonamido)ethyl-m-toluidine	Red-violet.
Do	N-ethyl-N- β -(methanesulfonamido)ethyl-m-toluidine	Pink.
Do	N,N-di- β -hydroxyethyl-m-chloroaniline	Do.
Do	N-methyl-N- β -(phenylcarbamyl)oxyethyl-m-toluidine	Orange-red.
Do	N-ethyl-N- β -acetoxymethyl-m-toluidine	Orange.
Do	N- β -cyanoethyl-N- β -benzyloxyethyl-m-toluidine	Scarlet.
Do	N-ethyl-N- β -, γ -dihydroxypropyl-m-toluidine	Red.
Do	N,N-di- β -hydroxyethyl-2-methoxy-5-acetamidoaniline	Red-violet.
Do	N,N-di- β -hydroxyethyl-m-chloroaniline	Orange-red.
Do	N-ethyl-N- β , γ -dihydroxyethyl-2-methoxy-5-acetamidoaniline	Red-pink.
Do	N,N-di- β -hydroxyethyl-m-chloroaniline	Pink.
Do	N,N-di- β -hydroxyethyl-2-methoxy-5-acetamidoaniline	Violet.

The following table illustrates the colors imparted by 3-methylthio-1,2,4-thiadiazolyl-5-azo-4'[N-ethyl-N- β -(phenylcarbamyl)oxyethyl]-aniline, a representative dye

These and the other azo dye compounds of our invention show good wash fastness and do not crock, especially in the case of linear aromatic polyester fabrics.

While numerous examples of the monoazo compounds of our invention have been given, these examples are illustrative and not limitative. Any of the 5-amino-1,2,4-thiadiazole compounds can be diazotized and coupled with an aniline coupling component free of a water-solubilizing group to obtain compounds of our invention.

As previously indicated, the new monoazo compounds of our invention are dyes for cellulose alkyl carboxylic acid ester, having 2 to 4 carbon atoms in the acid groups thereof, nylon, polyester and acrylonitrile polymer textile materials. In addition to these textile materials graft polymers such as those described in U.S. Patents 2,620, 324, 2,649,434, 2,657,191 and 2,827,450 can be dyed with our new monoazo dye compounds. The textile materials referred to herein can be dyed using known dyeing methods and can be in any desired form such as fiber, filament, yarn or cloth form, for example. Our new monoazo dyestuffs can be directly applied to said textile materials in the form of an aqueous suspension which can be prepared by finely grinding them to a paste in the presence of a sulfonated oil, sodium lignin sulfonate, or other suitable dispersing agent and dispersing the resulting paste in water.

The following example illustrates one satisfactory way in which our new monoazo dye compounds can be used to dye graft polymer and acrylonitrile polymer textile materials. 1 gram of dye is dissolved by warming in 5 ml. of ethylene glycol monomethyl ether. A 2% aqueous solution of a nonionic surfactant, such as Igepal CA (a polymerized ethylene oxide-alkylphenol condensation product), is added slowly until a fine emulsion is obtained and then the dye mixture is brought to a volume of 200 ml. with warm water. 5 ml. of a 5% aqueous solution of formic acid or acetic acid are added and then 10 grams of fabric made from an acrylic fiber are entered. In the case of fabrics made of Orlon 42 fiber the dyeing is carried out at the boil for one hour. In the case of fabrics made of Verel acrylic fiber the dyebath temperature should not exceed 90° C. in order to avoid damage to the fiber. The dyed material is then washed well with hot water and dried.

The foregoing dyeing example is merely illustrative of the manner in which the new monoazo dye compounds of our invention can be applied to graft polymer and acrylonitrile polymer textile materials. Larger or smaller amounts of dye can be employed, for example. Similarly, dyeing assistants other than Igepal CA can be employed.

The same procedure can be used in the case of linear aromatic polyester textile materials with the exception that a dyeing assistant ordinarily referred to as a "carrier" is used in the dyeing operation and the dyeing is carried out at the boil. Butyl benzoate, o-phenylphenol, p-phenylphenol, salicylic acid, methyl salicylate and benzoic acid are illustrative of the carriers that can be employed. Polyester textile materials can also be dyed by the methods described in U.S. Patents 2,757,064 and 2,880,050, for example.

Nylon and said cellulose alkyl carboxylic acid ester textile materials can be dyed, for example, by the procedure described in U.S. Patent 2,785,157. Direct dyeing operations can, with advantage, be conducted at temperatures of about 70° C.-90° C. but any suitable temperature can be used. Thus, the textile material such as cellulose acetate, for example, to be dyed or colored is ordinarily added to the dye bath at a temperature lower than that at which the main portion of the dyeing is to be effected. A temperature approximating 45° C.-55° C., for example, can be used, following which the temperature is raised to that selected for carrying out the dyeing operation. The temperature at which the dyeing is conducted may, of course, be varied somewhat depending upon the particular material undergoing coloration. As is understood by those skilled in the dyeing art, 70

the intensity of dyeing can be varied by varying the proportion of dye to material undergoing coloration. The amount of dye used can be, for example, 1/3% to 3% (by weight) of that of the textile material, although lesser or greater amounts of dye can be used.

Illustrative of such dyeing operations for cellulose ester and nylon textile materials with reference to the dyeing of cloth is the following procedure.

16 milligrams of dye are ground with an aqueous solution of sodium lignin sulfonate until well dispersed or alternately the dye can be dissolved in 5 cc. of hot ethylene glycol monoethyl ether. The dispersion or solution as the case may be, is then poured into 150 cc. of water to which a small amount of a surface-active agent such as 15 Igepon T ($C_{17}H_{33}CO_2N(CH_3)_2C_2H_5SO_3Na$) Nekal BX (sodium alkylnaphthalenesulfonate) or Orvus (sodium lauryl sulfate-type) has been added. The dye bath is then brought to the desired temperature and 5 grams of well wet-out cloth are added thereto. Dyeing is continued 20 until the proper shade is reacted. From time to time throughout the dyeing operation, the cloth is worked to promote even dyeing.

Although the invention has been described in considerable detail with reference to certain preferred embodiments thereof, it will be understood that variations and modifications can be effected without departing from the spirit and scope of the invention as described hereinbefore and as defined in the appended claims.

We claim:

1. The azo compounds having the formula:

35 wherein X represents a low carbon alkylsulfonyl radical and R represents the residue of an aniline coupling component free of water-solubilizing groups.

2. The azo compound having the formula:

3. The compound

4. The compound

5. The compound

6. The compound

7. The compound
